UNITED STATES PATENT OFFICE.

LANGDON MOORE, OF CHICAGO, ILLINOIS, ASSIGNOR TO WALTER P. MURPHY, OF CHICAGO, ILLINOIS.

SHEET-METAL CAR-END CONSTRUCTION.

Application filed October 1, 1920, Serial No. 568,582. Renewed June 15, 1922.

To all whom it may concern:

Be it known that I, LANGDON MOORE, a citizen of the United States, residing at Chicago, in the county of Cook and State 5 of Illinois, have invented new and useful Improvements in Sheet-Metal Car-End Constructions, of which the following is a specification.

This invention relates to improvements in 10 end structures for railway cars and more particularly to sheet metal ends for freight cars.

The end of a freight car is subject to very 15 severe shocks and stresses on account of the tendency of the cargo to shift when the train starts and stops and in switching and also to the tendency of the superstructure of the car to weave while the train is in motion. To strengthen this type of car, 20 ends have been constructed of one or more sheets or panels of metal, usually steel, which sheets or panels are formed with corrugations for rigidifying the structure to more readily meet impacts from without, 25 cargo thrusts from within, and the racking strains from weaving.

It is the object of this invention to provide an end of the sheet metal type which is adaptable to either wooden car frames 30 or all metal freight cars and that may be employed for strengthening gondola cars, box cars, or other similar cars. It is a further object of this invention to provide the sheets or panels of the end with corrugations of particular contour that from their 35 form and duration are peculiarly adapted to meet the stresses and strains already described. While the corrugations are preferably formed parallel, their relation to each 40 other or their direction is immaterial, likewise the corrugations may be all pressed from one side of the sheet of metal or may be formed from opposite sides, as desired.

While the preferred form of this invention 45 is illustrated upon the accompanying sheets of drawings, yet it is to be understood that minor detail changes may be made without departing from the scope thereof.

50 In the drawings:

Figure 1 is a view in end elevation of a box car illustrating an embodiment of this invention.

55 Figure 2 is a view in horizontal section through the end taken on the line 2-2 of

Figure 1, illustrating the attachment of the end to a car having a wooden frame.

Figure 3 is an enlarged detail view in 60 vertical section taken on the line 3-3 of Figure 2.

Figure 4 is an enlarged detail view in 65 vertical section taken on the line 4-4 of Figure 2.

Figure 5 is an enlarged detail view in 70 vertical section taken on the line 5-5 of Figure 2.

Figure 6 is an enlarged detail view in 75 vertical section taken on the line 6-6 of Figure 2.

Figure 7 is an enlarged detail view in 80 front elevation of a fragment of the corner of an end sheet or panel, partly in section.

Figure 8 is an enlarged detail sectional view taken on the line 8-8 of Figure 7.

The box car end, as illustrated, comprises 85 two or more sheets or panels 1, preferably of pressed steel, which are attached to the corner posts, end plate and end sill in the usual manner. Figure 2 illustrates a means of attaching the panels to the wooden corner posts 2 by flanging the ends of the panel 90 and securing the flanges to the posts.

A plurality of parallel strengthening corrugations or ribs are formed in each panel 1 which merge at their ends into the plane 95 of the panel so that the panel has a flat marginal portion about its edges.

The ribs or corrugations are shown in the drawing as pressed from the same side of the metal sheet and decrease constantly in 100 depth from center to ends, as shown in Figure 2. The contour of the corrugations at the center is shown in Figure 3 from which it is seen that the alternate main walls 3 are substantially flat and parallel, form similar angles to the panel and are preferably of less depth than the width of the portions 4 connecting them. The connecting portions are substantially flat and of equal width, in cross section, connecting the adjacent ends of 105 the main walls and lie in planes substantially parallel to the panel. As the depth decreases from center to ends, the main walls, maintaining substantially the same angular relation to the panel, decrease constantly and proportionately in width with the connecting portions on both sides of said walls constantly and proportionately increasing in width with their longitudinal center lines 110 parallel and maintaining, in cross section,

60

105

110

their parallel relation to the plane of the panel until the oppositely disposed connecting portions merge into their respective main walls and into each other in the plane of the panel, as shown in Figures 4, 5 and 6 and also in Figure 7.

A wooden lining 5 is preferably provided upon the interior of the end and a number of filler blocks 6 are received within and attached to a number of the ribs to which the lining is nailed, the blocks being beveled and tapered to fit the ribs or corrugations and support the lining parallel to the end as shown.

15 In this form of ribbed or corrugated panel, as the width of the oppositely disposed connecting portions increase similarly and proportionately to the decreasing depth from center to ends and as the angular relation 20 to the panel of the main walls remains the same throughout their length, the neutral axis of the panel on each side of the center lies in a plane midway between the planes of the oppositely disposed connecting portions and an equal amount of metal will be disposed at a distance on each side of the neutral axis, which, in cross section, will vary proportionately to the varying depth, thereby forming a strengthening member 25 which increases in its effectiveness from ends to center with the greatest strength at the center of the panel where it is most needed to meet the stresses and shocks to which it is subject.

30 35 What I claim is:

1. A metal panel for car ends having a plurality of corrugations therein formed with side walls and connecting portions, said connecting portions increasing constantly in 40 width from center to ends and merging into each other at their ends.

2. A metal panel for car ends having a plurality of corrugations therein formed with side walls of constantly decreasing 45 width from center to ends, and connecting portions increasing constantly in width from center to ends, said connecting portions merging into each other at their ends.

3. A metal panel for car ends having a 50 plurality of corrugations therein formed with side walls of constantly decreasing width from center to ends, and connecting portions constantly increasing in width from center to ends, said connecting portions merging into each other and into their respective side walls at their ends.

4. A metal panel for car ends having a 55 plurality of corrugations therein formed with side walls maintaining a constant angular relation to the plane of the panel throughout and decreasing constantly in width from center to ends, and connecting portions having a constant angular relation to the plane of the panel from ends to center and constantly and similarly increasing

in width in proportion to the side walls from center to ends.

5. A metal panel for car ends having a plurality of corrugations therein formed with side walls maintaining a constant angular relation to the plane of the panel throughout and decreasing constantly in width from center to ends, and connecting portions having a constant angular relation to the plane of the panel from ends to center and constantly and similarly increasing the width in proportion to the side walls from center to ends, said connecting portions merging into each other, into their respective side walls and into the panel at their ends. 70

6. A metal panel for car ends having a plurality of corrugations formed therein with side walls connecting inner and outer portions in planes spaced apart, said inner and outer portions being equal in width at any cross section of the corrugations. 85

7. A metal panel for car ends having a plurality of corrugations formed therein with side walls connecting inner and outer portions in planes spaced apart and converging, said inner and outer portions being equal in width at any cross section of the corrugations. 90

8. A metal panel for car ends having a plurality of corrugations formed therein with side walls connecting inner and outer portions in planes spaced apart, said inner and outer portions being equal in width at any cross section of the corrugations, said corrugations terminating within the edge of the panel. 95

9. A metal panel for car ends having a plurality of corrugations formed therein with side walls connecting inner and outer portions in planes spaced apart and converging, said inner and outer portions being equal in width at any cross section of the corrugations, said corrugations terminating within the edge of the panel. 105

10. A metal panel for car ends having a plurality of corrugations formed therein projecting in opposite directions from their neutral plane, said corrugations spaced apart distances equal to their width. 115

11. A metal panel for car ends having a plurality of corrugations formed therein projecting in opposite directions from their neutral plane, said corrugations spaced apart distances equal to their width, and varying in width from their middle to their end. 120

12. A metal panel for car ends having a plurality of corrugations formed therein projecting in opposite directions from their neutral plane, said corrugations spaced apart distances equal to their width, and varying in depth from their middle to their end. 125

13. A metal panel for car ends having a 130

plurality of corrugations formed therein projecting in opposite directions from their neutral plane, said corrugations spaced apart distances equal to their width, and 5 varying in width and depth from their middle to their end.

14. A metal panel for car ends having a plurality of corrugations formed therein comprising side walls connecting inner and 10 outer portions in planes spaced apart, said inner and outer portions increasing in width from adjacent the center of the ends of said corrugations, said inner and outer portions being equal in width at any cross section of 15 said corrugations.

15. A metal panel for car ends having a plurality of corrugations formed therein comprising side walls connecting inner and

outer portions in planes spaced apart, said inner and outer portions increasing in width 20 from adjacent the center of the ends of said corrugations, said inner and outer portions being equal in width at any cross section of said corrugations, said corrugations terminating within the edge of the panel. 25

16. A metal panel for car ends having a plurality of corrugations formed therein comprising side walls connecting inner and outer portions in spaced apart converging planes, said inner and outer portions increasing 30 in width from adjacent the center to the ends of said corrugations, said inner and outer portions being equal in width at any cross section of said corrugations.

LANGDON MOORE.
